UNITED STATES PATENT OFFICE.

MATTHEW F. BAYER, OF KENOSHA, WISCONSIN, ASSIGNOR TO SIMMONS COMPANY, OF KENOSHA, WISCONSIN, A CORPORATION OF DELAWARE.

PANEL-BED.

1,389,931.

Specification of Letters Patent.

Patented Sept. 6, 1921.

Application filed February 6, 1920. Serial No. 356,680.

To all whom it may concern:

Be it known that I, MATTHEW F. BAYER, a citizen of the United States, residing in the city of Kenosha, county of Kenosha, 5 and State of Wisconsin, have invented certain new and useful Improvements in Panel-Beds, of which the following is a specification.

My invention relates to improvements in 10 panel beds or beds of the up-ending type, in which type of bed, folding is effected by raising the foot or outer end of the bed and swinging the bed substantially in a vertical plane around a movable or stationary horizontal axis.

Beds of this type, when up-ended, may 15 readily be concealed, either by mounting the bed on a rotatable panel or door, or otherwise screening the bed when it has 20 been folded and is not in use.

The principal objects of my invention are to provide a wall bed so boxed that the operation thereof will require a minimum of 25 manual strength; to provide a wall or panel bed of the class described in which the balancing force is applied in substantial accordance with the balancing requirements regardless of the position of the bed; to provide a construction having a head end 30 which does not interfere with the operation of the bed; to provide a head end which will automatically assume its proper position when the bed is unfolded; to provide a bed construction having relatively few 35 parts and those parts of substantial and rugged character; to provide a construction comparatively free from unwieldy or unsightly parts, which will interfere with or damage the bed clothing or the occupant 40 of the bed; to provide a construction which shall be of simple and economical manufacture, while being practical and efficient in use and operation and in general to provide an improved up-ending bed construction of 45 the character referred to.

In the drawings accompanying this application, Figure 1 is an elevation of a bed equipped with my invention.

Fig. 2 is a similar elevation showing the 50 bed in an intermediate position between its folded and unfolded positions.

Fig. 3 is a view similar to Fig. 1 showing the bed completely folded or in vertical position.

Fig. 4 is a cross section taken on the line 55 4—4 of Fig. 1.

Fig. 5 is a section taken on the line 5—5 of Fig. 4.

Referring to the drawings, 10 represents the wall or a panel to which the bed as a 60 whole is connected.

The bedstead frame comprises a head end 11 and a foot end 12, both the head and foot end being movably connected with the 65 respective ends of the main frame of the bedstead. Said main frame of the bedstead comprises a pair of side rails 13, which in the present instance, are of tubular formation and are equipped with suitable risers 14 for supporting the flexible fabric 15, said 70 flexible bed fabric 15 being preferably of the link or any other approved type, and is connected by means of helicals 16 to cross-angles 17 and 18.

The mattress 19, indicated by means of 75 dotted lines in Fig. 1, and the bed-clothes, not shown, may if desired, be secured in position on the bed fabric 15, by means of a suitable clamping mechanism 20, which clamping mechanism, however, forms no 80 part of my present invention, but simply serves to prevent the mattress and bed-clothes from slipping down when the bed is up-ended.

As shown in Figs. 1, 2 and 3, the foot end 85 12 is folded with reference to the frame 13, such foldability being effected by means of a pair of dissimilar links 21 and 22 which nest with reference to each other as shown in Fig. 3 when the bed is completely folded, 90 while when the bed is unfolded, said links serve to maintain the foot end 12 in vertical position and brace the same.

A suitable catch 23 adapted to hook under one of the links 21 and pivoted on the side 95 of the cross-angle 18, may be employed to lock the link 21 in horizontal position when the bed is unfolded, and thereby prevent movement of the foot end 12 relative to the bedstead frame.

At each side of the wall or supporting panel 10, there is firmly secured a vertically extending structural steel member 24, for instance, an angle iron section as shown best in Fig. 5. One of the flanges of said angle iron 24 is folded over as shown best at 25 in Fig. 4 and perforated to serve as a support for a fixed pivot pin 26. Said pivot pin 26 100 105

serves as a connection or fixed pivot for the upper end of a rigid link 27 which extends outwardly and downwardly from said pivot. The lower end of said link 27 is pivotally connected to a pin 28 mounted in a small bracket 29, secured on the side-bar 13, intermediate the length thereof but adjacent the head-end of the frame. If desired, a cross angle iron member 30 may be employed for 10 uniting together the brackets on the opposite sides of the bedstead frame.

As shown best in Figs. 2 and 4, the main bedstead frame is formed with what may be termed a sub-head which, when the main or 15 visible head end 11 is elevated, forms a continuation thereof and prevents the pillows and bedding from moving toward the panel. Said sub-head comprises a horizontally extending cross-member 31 which is supported 20 on the upper ends of a series of intermediate uprights or fillers 32 and side uprights 33 which side uprights 33 are braced to the side bars 13 by means of inclined strap members 34 which serve to maintain the sub-head 25 in rigid position at right angles to the line of the side-bars 13.

Each end of the top bar 31 of the sub-head is formed with an upstanding lug 35 to which is pivoted by means of a pin 36, the 30 lower end of the side 37, so that the lower end of the main frame will partake substantially of the movement of the upper end of the sub-head. In order to maintain the head-end 11 always in a vertical position, 35 the lower ends of the side-ends 37 are extended down a substantial distance below the pivot 36, so that when pressure is applied to said pivot in a direction to force the same toward the panel, both the upper portion and 40 the lower end of the head-end will be forced in the same direction.

During the folding movement of the bed which will be described later, the pivots 36 at the top of the sub-head are moved vertically and slidably with reference to the support 10. Inasmuch as there is, due to the arrangement, considerable thrust imposed upon said pivot which thrust is supported by the sliding main-head 11, anti-friction 45 means preferably are employed in connection with said sliding movement. Said anti-friction means comprise a pair of rollers 38 indicated best in Fig. 5 and mounted on horizontal pins disposed transversely in the side tubes 37. The position of the pivots 39 is such as to enable the rollers 38 to project through slotted apertures in the walls of the tubes 37. It will be understood that each of the side tubes 37 is equipped with a pair of 50 said rollers 38, the rollers being disposed on either side of the pivot pins 36, so as to distribute pressure and at the same time maintain the main head-end 11 in vertical relation.

65 Referring now to the balancing mechanism

it will be observed that the lower ends of the structural steel uprights 24 are united together by an angle iron sill 40, said sill 40 being suitably braced by oblique straps or bars 41. On the horizontal flanges of said sill 40 are riveted or otherwise suitably secured, a pair of short angle iron sections 42, so positioned as to bring the vertical flange thereof a short distance away from the surface of the support and permit connection 70 of the hooked ends 43 of a set of balancing springs 44.

It will be understood that the said vertical flange of the angle iron section 42 is suitably perforated to admit the ends of the said hooks 43 and to permit the spring to assume a substantially horizontal position as shown in Fig. 3 as well as a vertical position as shown in Fig. 1.

The upper ends of the springs 44 of each bank are similarly connected to the horizontal portion of a T-shaped link 45, the upper end of which is folded to form a hinged part 46, the pin 47 of which is secured in a bracket 48. The bracket 48 may be formed of a piece of structural iron or steel bent to its required shape to admit the hinged part 46 of the link 45.

Referring to Figs. 1, 2 and 3, it will be observed that in the position shown in Fig. 95 1, the T-shaped link 45 constitutes simply a straight pulling connection between the pivot pin 47 rigid with the frame and the part 42 rigid with the support, and this relation is maintained until when during the 100 operation of folding the bed, the position indicated in Fig. 2 is reached. When, however, the folding operation is continued beyond the point shown in Fig. 2, the back of the T-shaped link 45 engages the under side 105 of the cross angle 49, and during further movement, the link 45 becomes in effect a continuation of the flange of the angle 49 as shown best in Fig. 3.

The operation of the device may now be 110 briefly described. Assuming that the bedstead is in horizontal or unfolded position as shown in Fig. 1, and it is desired to fold or up-end the bed, the foot end of the bed is first unlocked so as to make it possible 115 for it to fold against the frame and the foot end of the bed is lifted by hand. During the early part of the movement, the springs 44 serve to substantially balance the weight of the bed upon the pivot 28, so that a comparatively small amount of manual strength is required to raise the foot.

The characteristics of the springs 44 are such that as the center of mass of the bed moves toward the pivot 28, that is to say, as 125 the horizontal spacing decreases, there will be a loss in tension of said springs, corresponding substantially with the reduction in balancing force required to keep the bed in equilibrium and substantially balanced on 130

the pivot 28. This condition will obtain until the position, substantially as shown in Fig. 2 is reached, when the line of the springs will be substantially parallel or co-incident 5 with the general line of the rails of the bed-frame. At this instant the balancing effect of the springs will be negligible by reason of the relative positions of the link 27 and the pivots 28 and 36 and the bed will be in substantial equilibrium independent of any external applied balancing force.

During the movement of the parts from the position shown in Fig. 2 to the completely folded position shown in Fig. 3, the 15 arrangement of the links and pivots causes the weight of the bed to in effect overbalance, and unless there were some restricting influence applied, the foot of the bed would swing up suddenly out of control of the person operating the same.

However, with my improved arrangement, a restricting influence on such sudden jack-knife action is provided, by reason of the fact that during the final position of the 25 folding movement, the action of the springs 44 is reversed. In other words, the springs are extended and thus resist the folding or swinging movement. Said resisting influence of the springs 44 is rendered fully effective by the peculiar action of the T-shaped link 45 which gives a considerable extension to the springs 44 during the final position of the folding movement.

It will be seen that in swinging the bed 35 through 90° from open to closed position or vice versa, the springs also change their angular position about 90° with reference to the floor. Hence, with reference to the bed the springs move through an angle of 40 180°, such large angle of movement being made possible by reason of the pivotal action of the link 45.

It will be observed that when the bed is unfolded or extended as shown in Fig. 1, the 45 only part of the mechanism which is visible is the link 27 and the head end 11 is raised in such position that the appearance of an ordinary bedstead is produced. It will also be observed that the sub-head to which the

bottom of the main head end 11 is connected 50 serves to prevent the pillows from falling down when the bed is folded as well as preventing them from moving out of place when the bed is being used.

The details of construction herein depicted 55 being merely illustrative of a single application of my invention, the scope of my invention should be determined by reference to the appended claims, said claims being construed as broadly as possible consistent with 60 the state of the art.

What I claim is:

1. In a panel bed, the combination of a relatively stationary vertical support, an outwardly and downwardly inclined link 65 having its upper end pivotally connected to said support, a bed frame swingingly mounted relative to said support and having an intermediate point in its length pivotally connected to the lower end of said link, 70 whereby the end of said bed-frame is forced toward said support, a supplemental head frame vertically slidable on said support, vertically spaced anti-friction rollers interposed between said support and said supplemental frame and means pivotally connecting said bed frame with the supplemental frame intermediate said rollers.

2. In a panel bed, the combination of a relatively stationary support, a rigid link, 80 having one of its ends pivotally connected to the upper portion of said support and having its lower end extending outwardly and downwardly relative to said upper end, a bed-frame having an intermediate point in 85 its length adjacent one end thereof, pivotally supported by the lower end of said link, the arrangement including balancing means whereby the weight of said bed when unfolded, is substantially carried by said 90 pivot, and a supplemental bed-frame portion vertically slidable relative to said support and having vertically spaced parts engaging said support and connected pivotally intermediate said parts to the end of said bed- 95 frame.

MATTHEW F. BAYER.
